MEASURING TOP FOR CONTAINERS

Scott E. Donelson, Marion, Ohio

Application July 3, 1936, Serial No. 88,699

4 Claims. (Cl. 221—102)

This invention relates to dispensers especially adapted for dispensing granular or powdered matter such as tooth powder from a container and has for the primary object the provision of a device of this character which may be readily added to a container during the manufacture thereof without materially increasing the cost of the latter and which besides providing an efficient closure for the container, will permit the contents of the container to be dispensed in predetermined amounts by a simple manipulation thereof and also will act to force the measured amount from the container.

With these and other objects in view, this invention consists in certain novel features of construction, combination and arrangement of parts to be hereinafter more fully described and claimed.

For a complete understanding of my invention, reference is to be had to the following description and accompanying drawing, in which—

Figure 1 is a fragmentary end view, partly in section, illustrating a container equipped with a dispenser constructed in accordance with my invention.

Figure 2 is a sectional view taken on the line 2—2 of Figure 1.

Figure 3 is a sectional view taken on the line 3—3 of Figure 2.

Figure 4 is a fragmentary vertical sectional view showing the position occupied by the dispenser prior to the dispensing operation.

Figure 5 is a perspective view illustrating the dispensing element.

Figure 6 is a fragmentary end view, partly in section, illustrating a modified form of my invention.

Figure 7 is a sectional view taken on the line 7—7 of Figure 6.

Figure 8 is a sectional view taken on the line 8—8 of Figure 7.

Figure 9 is a perspective view illustrating the dispensing element of my modified form of invention.

Referring in detail to the drawing, the numeral 1 indicates a conventional type of container employed for granular or powdered material such as tooth powder and is equipped with the usual discharge neck 2. In adapting my invention to a container of this kind the discharge neck 2 is closed by an end wall 3 in which is formed a slot 4. Extending centrally through the end wall 3 is a rivet 5 formed on a cover 6. The cover 6 overlies the end wall 3 and is of the flanged type, as shown at 7, and further is pro-

vided with a discharge opening 8 adapted to move into and out of register with the slot 4 when desiring to dispense the contents of the container.

Mounted on the rivet 5 and fixed thereto is a dispensing element 9 of substantially segmental shape. The element 9 is adapted to rotate with the cover 6. The element 9 tapers from one edge towards an opposite edge to form thereon a cam face 10 opposing the end wall 3. The element 9 due to its shape, provides a portion of a helix so that during the rotation of the element 9 it will produce a feeding action on the container content. The cam face 10 cooperating with the end wall 3 acts as a follower for the purpose of urging the material in the neck 2 when the container 1 is inverted towards and through the slot 4. The neck 2 with the dispensing element 9 located therein presents a chamber or space of a size that will accommodate a certain amount of the content of the container when the latter is placed in an inverted position so that on rotating the cover to align the opening 8 thereof with the slot 4, the dispensing element sweeps or pushes material in the space or chamber towards and through said slot or opening 8 so that only the proper amount of material will be discharged for use on a tooth brush for a cleaning operation of the teeth.

Spaced stops 11 are arranged in the neck 2 for the purpose of limiting the rotation of the dispensing element 9 in opposite directions, also the cover 6. The dispensing element 9 when engaged with one of the stops places the opening 8 of the cover out of alignment with the slot 4, consequently closing the container. The dispensing element 9 when moved from engagement with the last-named stop to engage the other stop brings about the aligning of the opening 8 of the cover with the slot 4 so that during said movement of the dispensing element the container 1 will be opened so that the predetermined amount of the content of the container acted on by the dispensing element will be shoved towards and through the slot and the opening 8.

Referring to my modified form of invention, as shown in Figures 6 to 9, inclusive, the cover 6 is eliminated and the neck 2 of the container 1 is provided with a discharge opening 12. A rivet 13 is rotatably supported by the end wall of the neck 2 and has secured to its outer end a finger piece 14. A dispensing element 15 is secured to the rivet 13 and is of substantially segmental shape, as shown in Figure 9. A partition 16 is formed in the neck 2 and extends from the at-

tached portion of the element 15 to one edge of the opening 12 and has a compound curve, as clearly shown in Figure 8. One edge of the dispensing element 15 has a compound curve 17. Between the edge 17 and the partition 16 is formed a chamber in the neck to receive an amount of the content of the container 1 when placed in an inverted position and with the dispensing element 15 in engagement with a stop 18. The amount of content received in said space is sufficient or proper for one cleaning of the teeth. To dispense the predetermined amount of material or powder from the space, the finger piece 14 is manipulated, moving the dispensing element 15 from the stop 18 towards and in engagement with the partition 16, causing the measured amount of material to be swept towards and through the opening 12.

The element 15 when moved into engagement with the partition 16 closes the opening 12 and consequently prevents the content of the container from escaping accidentally or during the non-dispensing operation.

While I have described my invention as principally adaptable to containers for tooth powder, it is to be understood that my invention may be successfully employed on any container wherein it is desired to dispense the contents in measured amounts and to act as a closure for the container.

Having described the invention, I claim:

1. In combination with a container having a neck provided with a slot in the end of said neck, a substantially segmental-shaped dispensing element journaled in the neck and tapering from one edge to another edge thereof for cooperating with the neck when in one position to define a space of a size to receive a predetermined amount of the content of the container, and means for moving said element from said position towards the slot to sweep the measured amount of the content towards and through the slot.

2. In combination with a container having a neck provided with a slot, a pin journaled in the neck, a dispensing element secured to the pin and located in the neck and cooperating therewith when in one position in defining a space of a size to receive a predetermined amount

of the content of the container, a cap having an opening secured to said pin and acting to close the slot during said position of the dispensing element and may be rotated to open the slot by aligning the opening with said slot and to bring about movement of the dispensing element from said position towards the slot to sweep the measured amount towards and through the slot and opening.

3. In combination with a container having a neck provided with a slot, a pin journaled in the neck, a dispensing element secured to the pin and located in the neck and cooperating therewith when in one position in defining a space of a size to receive a predetermined amount of the content of the container, a cap having an opening secured to said pin and acting to close the slot during said position of the dispensing element and may be rotated to open the slot by aligning the opening with said slot and to bring about movement of the dispensing element from said position towards the slot to sweep the measured amount towards and through the slot and opening, said dispensing element tapering from one edge towards another edge to form a cam face, which cam face diverges from a wall of the neck.

4. In combination with a container having a neck provided with a slot, a pin journaled in the neck, a dispensing element secured to the pin and located in the neck and cooperating therewith when in one position in defining a space of a size to receive a predetermined amount of the content of the container, a cap having an opening secured to said pin and acting to close the slot during said position of the dispensing element and may be rotated to open the slot by aligning the opening with said slot and to bring about movement of the dispensing element from said position towards the slot to sweep the measured amount towards and through the slot and opening, said dispensing element tapering from one edge towards another edge to form a cam face which cam face diverges from a wall of the neck, and stops for limiting the rotation of the dispensing element in either direction.

SCOTT E. DONELSON.
